(57) **CLAIM**

The ornamental design for an audio mixer, as shown and described.

DESCRIPTION

FIG. 1 is a perspective view of an audio mixer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of an indicated portion shown in rectangle 9 of FIG. 1;

FIG. 10 is an enlarged view of an indicated portion shown in rectangle 10 of FIG. 2;

FIG. 11 is an enlarged view of an indicated portion shown in rectangle 11 of FIG. 7; and,

FIG. 12 is the enlarged view of FIG. 11, showing light emitting portions of the audio mixer in an illuminated state. The dashed broken lines illustrate portions of the audio mixer that form no part of the claimed design. The dot-dash broken lines represent boundaries of the enlarged portion and form no part of the claimed design. The surface shading in FIG. 11 is omitted in FIG. 12 so as to clearly represent the illuminated state in FIG. 12. The radiating lines in FIG. 12 represent the glowing visual effect created by light emanating from the light emitting portions of the audio mixer.
